United States Patent Office

Des. 193,975
Patented Nov. 6, 1962

193,975

VEHICLE

Samuel M. Highberger, Birmingham, and Norbert T. Kuypers, Warren, Mich., assignors to Clark Equipment Company, a corporation of Michigan

Filed Feb. 26, 1962, Ser. No. 68,979

Term of patent 14 years

(Cl. D14—3)

FIG. 1

FIG. 2

FIG. 3

FIG. 4

FIG. 5

FIG. 6

FIGURE 1 is a right front quarter perspective view of a vehicle, showing our new design;

FIGURE 2 is a left side elevational view thereof;

FIGURE 3 is a right rear quarter perspective view thereof;

FIGURE 4 is a rear elevational view thereof;

FIGURE 5 is a front elevational view thereof; and

FIGURE 6 is a plan view thereof.

The dominant features of our design reside in the portions illustrated in solid lines.

We claim:

The ornamental design for a vehicle, as shown and described.
